HENRY KREES, OF DETROIT, MICHIGAN, ASSIGNOR TO PACKARD MOTOR CAR COMPANY, OF DETROIT, MICHIGAN, A CORPORATION OF MICHIGAN

METAL WORKING MACHINE

Application filed December 16, 1926. Serial No. 155,262.

This invention relates to metal working machines, and while capable of general use, is particularly adapted for machining the walls or surfaces of compression recesses formed in cylinder heads for hydrocarbon motors.

It has heretofore been proposed to cast cylinder heads with compression recesses there-in of tapered depth, but this method is defective in that irregularities frequently occur 10 in the contours of the compression recesses, with the resulting variation in compression of the several cylinders of the hydrocarbon motor. It has further been proposed to machine the walls or surfaces of the tapered 15 compression recesses so as to avoid the disadvantage above referred to, and it is the principal object of this invention to provide a novel manner of machining a type of tapered compression recess that is undercut at its 20 deeper portion around the valves to provide certain recognized advantages over tapered compression recesses heretofore employed.

Other objects of this invention are to provide improved mechanism for machining cylinder head compression recesses of tapered depth, which enables such recesses to be undercut at the deeper portions thereof around the valves; which includes a swinging work-holder or cradle that is automatically oscillated during the operation of the machine 25 and controlled so that the mill or cutter may be entered in and withdrawn from the work at the shallower part of the compression recess; which embodies, in addition to the swinging work-holder, a mill or cutter that is automatically moved in directions angularly related to each other and to the direction of movement of the work-holder, so that the compression recess may be machined and undercut in a closed path beginning and ending 30 at the shallower part of the recess; which produces, in addition to the aforesaid movements of the mill or cutter and the work-holder, a movement of one with respect to the other which enables the angle that the mill or cutter makes with the work to be varied whereby a part of said work may be more expeditiously machined; and which is a simply constructed, inexpensive and highly efficient mechanism for machining and under-

cutting recesses of any desired physical shape.

In order to more clearly understand this invention, reference may be had to the accompanying drawings which illustrate one 55 embodiment of the inventive idea and wherein

Fig. 1 is a front view of a metal working machine embodying the present invention;

Fig. 2 is a side view of the machine illustrated in Fig. 1 looking from the right thereof;

Fig. 3 is an enlarged perspective view with parts omitted, showing the driving connections for the various movable parts of the 65 machine;

Fig. 4 is an enlarged perspective view, partly in section, of a yoke and a cradle or work support trunnioned thereon;

Fig. 5 is a perspective view of the cradle or work support shown in Fig. 4, looking from the rear thereof;

Fig. 6 is a bottom plan view of a cylinder head, showing diagrammatically the machining and undercutting operations;

Fig. 7 is an enlarged view of a rose end mill or cutter;

Fig. 8 is a sectional view on the line 8—8 of Fig. 6;

Fig. 9 is an enlarged view of another rose 80 end mill or cutter, and

Figs. 10, 11 and 12 are sectional views on the lines 10—10, 11—11, and 12—12, respectively, of Fig. 6.

Referring to the drawings, wherein like 85 reference characters designate like parts throughout the several views, 5 indicates the base of the machine provided at the rear thereof with a vertical column 6 having a forwardly curved head 7 that overhangs a 90 table 8 at the top of the base 5, (Figs. 1 and 2). Mounted on the forward face 9 of the head 7, as by ways 10, 10, is a vertically movable slide 11 that is normally fixed against movement during the operation of the machine but which may be adjusted vertically for purposes hereinafter set forth. This slide 11 has mounted thereon, as by ways 12, 12, a second vertically movable slide 13 95 provided on the front face thereof with

ways 14, 14, on which is mounted a horizontally movable slide 15 that carries in suitable bearings thereon, the vertical spindles 16, 16 of a plurality of rose end mills or cutters 17, 17 disposed in spaced relation and arranged in a row at the front of the machine.

The table 8 is provided with ways 18, 18 that extend from the front toward the rear 10 of the machine, and mounted on the ways 18, 18 is a horizontally movable slide 19 that carries a yoke 20 which is bolted or otherwise suitably secured to slide 19 at 21, 21. Trunnioned in suitable bearings 21', 21', on the upper ends of the yoke arms 22, 22 is a swinging work-holder or cradle 23 that is provided on the bottom 24 thereof with curved slotted guides 25, 25, which engage guides 26, 26 of corresponding curvature formed on guide blocks 27, 27 (Figs. 2 and 4). These guide blocks 27, 27 are provided on the bottoms thereof with guides 28, 28 slidably mounted in slots 29, 29 formed in the yoke 20, there being machine screws 30, 30 threaded through 25 suitable openings in the yoke 20 so as to engage opposed extremities of one of the guides 26, 26 and thereby serve as means for adjusting the same with respect to one of the guides 25, 25. The other guide 26 may be adjustably secured to the yoke 20 by machine screws 30', 30' which extend through suitable openings in the corresponding guide block 27 and are threaded into the yoke 20. The cradle 23 has bolted or otherwise suitably secured to the top thereof, an open frame 31 through the elongated opening 31' of which the mills or cutters 17, 17 are inserted and withdrawn so as to be engaged with or disengaged from the work. As herein disclosed, the work consists of a cylinder head 32 (Figs. 1, 2 and 6) that is supported in the cradle in an inverted position against the open top frame 31 and provided with compression recesses 33, 33 of tapered depth 40 which are machined and undercut in accordance with the present invention. The cylinder head 32 is placed within the cradle through the front thereof which is open for this purpose, said head preferably being first 45 engaged with pins 34 and 35 on the cradle and thereafter clamped against the frame 31 of the cradle by a clamping head 36. The clamping head 36 is rotatably secured on the upper end of a vertical screw-shaft 37 threaded through a suitable opening in the bottom 24 of the cradle and adapted to be 50 adjusted vertically whereby the work is clamped against the top or frame 31 of the cradle by the clamping head 36. The clamping head 36 is provided at the rear thereof with pins 36', 36' (Figs. 2 and 4) that project through slots 36'', 36'' in the rear wall of the cradle and serve to guide said clamping head as it is raised or lowered with the screw-shaft 55 55. Vertical adjustments of the screw-shaft

37 and the clamping head 36 are obtained by a hand-wheel 38 threaded on the screw-shaft 37 and rotatably mounted on the bottom of the cradle, the rim of this hand-wheel entering a recess 39 in the back of the cradle whereby said wheel is prevented from moving along the screw-shaft as the wheel is rotated. In order to prevent undue strain on the top and bottom walls of the cradle by the clamping of the work therein, said cradle is provided with a strut bar 40 that extends across the open front of the cradle and is pivoted at 41 to the frame 31 so that said strut bar may be swung upwardly out of the way when the work is being placed in the cradle. After the work has been placed in the work-holder or cradle, the bar 40 is swung downwardly and secured to the bottom wall of the cradle by a block 42 adjustably secured on the lower end of said bar which block engages the under side of a lug 43 on the bottom wall of the cradle. This lug 43 is slotted as shown in Fig. 4, to receive the lower end of the bar 40 and the block 42 is removably secured to said lug by a screw 43' or other suitable fastening means. After the lower end of the bar 40 has been secured to the bottom of the cradle, the work is clamped in the cradle as above described.

The cradle is oscillated and stopped automatically by means hereinafter described, and the timing of said means is such that when the cradle is stopped it will assume the full line position shown more clearly in Fig. 2, in which position the cylinder head 32 may be readily placed in the cradle so that on lowering the mills or cutters 17, 17 through the opening 31' they may be initially engaged in the tapered compression recesses 33, 33 at the shallower portions thereof. This initial engagement of the mills or cutters with the work may be obtained by any suitable means, but as here shown this means is preferably comprised by the following devices.

Journalled in a bracket 44 secured on the overhanging head 7 is a screw-shaft 45 (Fig. 2) that is threaded through a lug or fixed nut 46 on the back of the slide 11 and retained against displacement by collars 47, 47 that are fixed on the shaft 45 at the opposite sides of said bracket (Fig. 2). The upper end of this shaft 45 has fixed thereon a bevel gear 48 that meshes with a similar gear 49 rigidly secured on one end of a shaft 50 which is also journalled in the bracket 44. The opposite end of this shaft 50 carries a hand-wheel 51 which may be rotated to impart like motion to the screw-shaft 45 and thereby raise or lower the slide 11 and the parts mounted thereon.

The slide 13 is provided with open sided lugs 52, 52 adapted to receive bolts 53, 53 that are pivoted at 54, 54 on the slide 11 and provided on their outer ends with wing nuts 55, 55 that may be clamped on the lugs 52, 52 in order to produce raising and lowering move-

ments of the slides 13 and 15 with the slide 11 when corresponding movements are imparted to the latter by the screw 45 and described mechanism for operating the same. When it is desired to lower the mills or cutters 17, 17 into the cradle and work, the slides 13 and 15 are clamped to the slide 11 by the bolts 53, 53 and wing nuts 55, 55. Thereafter the hand-wheel 51 is turned to move the slide 11 so that the mills or cutters 17, 17 are lowered through the cradle opening 31' into the shallower portions of the compression recesses 33, 33. Movement of the slide 11 and the parts carried thereby is preferably counterbalanced by a weight 56 disposed within a housing portion 57 on the column 6 and secured to one end of a cable 58 which extends into the housing portion 57 through a suitable opening therein. This cable 58 passes over sheaves or pulleys 59, 59' and 60 mounted on the column 6 and the head 7 thereof respectively, and the opposite end of said cable is secured at 61 to the top of the slide 11. After the mills or cutters 17, 17 have been engaged in the compression recesses 33, 33 as above described, the drive for the cutters is then connected therewith to rotate the same and the cradle and the cutters are swung relatively to make an initial cut in the dome of each compression recess, said initial cut being such as to machine the major portion of the recess preparatory to profiling and undercutting operations that are performed by other mills or cutters 17', 17' (Figs. 1, 9, 10 and 11) on further movements of the cradle 23 and reciprocation of the slides 13 and 15.

The mechanism for driving the cutters and for swinging the cradle may be of any suitable construction, but as here shown, said mechanism is preferably comprised by the following devices. Mounted on a bracket 62 bolted or otherwise suitably secured to the column 6, is an electric motor 63 the armature shaft 64 of which has fixed thereon a pulley 65 over which passes a belt 66 (Figs. 1, 2 and 3). Said belt also passes over a pulley 67 fixed on the main driving shaft 68 of the machine, this shaft 68 being journalled in suitable bearings on the vertically movable slide 13. A suitable belt-tightener, such as a spring loaded idler pulley of conventional type, may be employed to maintain an even tension on the belt 66 if deemed desirable. Rigidly secured on the main driving shaft 68 is a worm 69 which meshes with worm-gears 70, 70 fixed on the cutter spindles, 16, 16 that are carried by the slide 15 as above described. Freely mounted on one end of the main driving shaft 68 is a bracket 71 in which is journalled a short shaft 72 (Fig. 3) having fixed on one end thereof a bevel gear 73 that meshes with a similar gear 74 rigidly secured on said main driving shaft. The opposite end of the short shaft 72 has a squared telescopic fit in one extremity of a shaft 75, the opposite end

of which is connected by a universal joint 76 with one end of a second short shaft 77 journalled in suitable bearings in the column 6 of the machine. This short shaft 77 has fixed on the opposite end thereof a bevel gear 78 which meshes with a similar gear 79 rigidly secured on the lower end of a vertical shaft 80 that is journalled in suitable bearings in the machine column 6.

The upper end of the shaft 80 has fixed thereon a worm-wheel 81 that meshes with a worm 82 loosely mounted on one extremity of a longitudinally disposed shaft 83 that is journalled in suitable bearings in the top of the column 6. The opposite extremity of the shaft 83 has fixed thereon a worm 84 that meshes with a worm-wheel 85 fixed on the upper end of a second vertical shaft 86 journalled in suitable bearings in the column 6. This shaft 86 extends downwardly into the base of the column 6 where it is provided with a worm 87 that meshes with and drives a worm wheel 88. The worm-wheel 88 is fixed on a horizontally disposed shaft 89 journalled in suitable bearings in the column 6 and carrying a cam 90. Engaged in the groove 90' of the cam 90 is a roller 91 mounted on a lever 92, the lower end of which is pivoted at 93 in the base of the column 6 (Figs. 1 and 3). Pivottally connected with the upper end of the lever 92 is one end of a rod 94 the opposite end of which is pivottally connected with a lug 95 that is formed on and extends rearwardly from the cradle 23. The rod 94 is preferably made in two parts connected for adjustment of the cradle 23 with respect to the cam 90, by a turnbuckle 96, and in order to provide maximum clearance for the rod 94 as it is moved by the cam 90 to swing the cradle 23, the slide 19 is preferably formed at the rear thereof with a slot 97 (Fig. 2) disposed in alignment with said rod.

The mills or cutters 17, 17 having been engaged in the shallower parts of the compression recesses 33, 33 as above described, the drive for said cutters is started as by throwing the switch for the motor 63. With the mills or cutters 17, 17 rotating and the parts in the position shown in Figs. 1 and 2, a clutch, to be presently described, is then tripped to connect the cradle operating mechanism with the main drive shaft 68 so that the cradle 23 is swung relatively to the mills or cutters, first rearwardly, and then forwardly, whereupon said clutch is operated automatically to disconnect the drive for the cradle which is stopped in the full line position shown in Figs. 1 and 2. This clutch may be of any suitable construction but as herein shown preferably includes and is operated by the following instrumentalities.

The worm 82 that is loosely mounted on shaft 83, has secured to or formed integrally therewith a cone clutch element 98 which is also loosely mounted on the shaft 83. Fixed

on the shaft 83 for sliding movement along the same is a cone clutch element 99 that is urged toward the clutch element 98 for engagement therewith by a compression spring 100 (Figs. 1, 2 and 3). This spring 100 is preferably housed in the hub of the clutch element 99 and is held under compression between said clutch element and a fixed abutment (not shown). The spring 100 moves the clutch element 99 into engagement with the clutch element 98 through the controlled action of a clutch operating lever 101 having a yoke 102 embracing the hub of the clutch element 99 and trunnioned thereon at 103, 103. The lower end of the clutch operating lever 101 is pivotally mounted at 104 on one end of a toggle formed by links 105 and 106 pivotally connected at 107 and mounted on a fixed pivot 108 carried by the overhanging head 7 of the column 6. A toggle operating rod 109 that is also pivotally connected at 107 to the toggle links depends therefrom and is pivotally connected at 110 to one end of a treadle 111 provided with a foot plate 111'. This treadle is pivoted at 112 on the base 5 of the machine and connected at 113 with one end of a spring 114, the opposite end of which is connected with a pin 115 located above the pivotal point 112 and secured to the base 5. The spring 114 normally tends to lift the treadle and pull the rod 109 downwardly so that the links 105 and 106 are held substantially in alignment and hold the clutch parts 98 and 99 disengaged. A pin 116 secured to the overhanging head 7 serves to prevent movement of the links 105, 106 downwardly beyond their substantially aligned position, and adjustment of the length of the rod 109 is provided for by making the same in two parts connected with a turnbuckle 117.

The shaft 89 has secured to one end thereof of a bevel gear 118 that meshes with a bevel gear 119 fixed on the lower end of a vertical shaft 120 journalled in suitable bearings on the base 5 and overhanging head 7. The upper end of said shaft 120 has fixed thereon a bevel gear 121 that meshes with a similar gear 122 secured on a horizontal shaft 123 that is journalled in suitable bearings on the overhanging head 7. The gearing 118, 119 and 121, 122 is such that the shafts 120 and 123 are driven at the same speed as the shaft 89 and the shaft 123 has adjustably secured thereon a disk 124 provided at diametrically opposite points with rollers 125 and 126, each adapted on a half revolution of the shaft 89 and the cam 90, to engage a cam 127 projecting from one side of a clutch operating lever 128. This lever 128 has a forked end 129 that engages over the shaft 123 and a yoke end 130 that is pivotally connected at 131, 131 with the upper end of the yoke 102.

In the position of the parts shown more clearly in Figs. 1 and 3, and with the mills

or cutters 17, 17 rotating in the shallower parts of the compression recesses 33, 33, the operator depresses the treadle 111, the depression of said treadle breaking the toggle 105, 106. Immediately upon breaking the toggle 105, 106 the spring 100 swings the lever 101 to the right about the pivots 131, 131 thereby coupling the clutch parts 98, 99 and connecting the drive for operating the cradle 23. The cradle is thus swung by the rod 94 and cam 90 as described, the shape of the portion of the cam groove 90' then engaged with the roller 91 preferably being such that on a half revolution of the shaft 89 the cradle will be swung once toward the rear and then once toward the front of the machine through a distance somewhat less than the distance between the shallower and deeper ends of the compression recesses 33, 33. After the drive for the cradle operating mechanism has been established, the disk 124 is rotated a half revolution, during which time the roller 125 rides onto the cam 127, whereupon the latter with the lever 128 is moved to the left against the action of spring 100 on lever 101. In this movement of the lever 101 to the left, the latter swings about the pivot 104 by reason of the fact that the operator has released the treadle 111 and the toggle levers 105, 106 are returned to their substantially aligned position by the spring 114. When the roller 125 engages the cam 127, the lever 101 will therefore disengage the clutch 98, 99 and disconnect the drive for the cradle operating mechanism, the cradle stopping at approximately its full line position shown in Fig. 2 of the drawings.

During the first half revolution of the cam 90 and the resulting movement of the cradle 23, the mills or cutters 17, 17 make initial cuts in the compression recesses 33, 33 and machine the major portion of the dome of each recess. These are straight cuts obtained without lateral movement of the work or cutters and are identical in configuration. The margins of one of these initial cuts is indicated diagrammatically at A in Fig. 6, and one of the mills 17, 17 and a cross-section of the initial cut produced thereby are illustrated in Figs. 7 and 8. The distance above referred to, through which the cradle 23 swings while the initial cuts are being made in the compression recesses 33, 33 is pointed out as being less than the distance between the shallower and deeper ends of the recesses, and the reason for this is that the cylinder head 32 herein illustrated has reentrant portions 32', 32' at the deeper ends of the compression recesses which portions preferably are not machined by the mills or cutters 17, 17. It will of course be understood, however, that the cradle 23 may be swung through any distance desired to meet various operating conditions, and that this initial or any other

swinging movement of the cradle may be regulated by the employment of any desired cam or cams suitable for the work at hand.

The initial cuts having been made in the recesses 33, 33 and the cradle stopped upon completion of the first half revolution of the cam 90 and disk 124, the drive for the cutter spindles 16, 16 is stopped as by again throwing the switch for the motor 63. The slides 11, 13 and 15 are then elevated by turning the handwheel 51, so that the mills or cutters 17, 17 are withdrawn from the work 32 and the cradle 23.

After the mills or cutters 17, 17 have been raised clear of the cradle, the rose end mills or cutters 17', 17' (Figs. 1, 9, 10 and 11) are substituted therefor and the several slides are lowered together by the handwheel 51 until said mills or cutters 17', 17' pass through the frame 31 of the cradle and engage the walls of the compression recesses 33, 33 at the shallower portions thereof. The bolts 53, 53 are then unclamped from the lugs 52, 52 and swung clear of the latter so that the slides 13 and 15 are free to move independently of the slide 11 which remains stationary at any desired position through its engagement with the screw 45. With the mills or cutters 17', 17' engaged in the work, it is ready for profiling and undercutting which preferably is a combined operation obtained by simultaneously rotating the mills or cutters 17', 17', swinging the cradle 23, and reciprocating the slides 13 and 15. The slide 19 may also be, and preferably is, reciprocated during this operation by means, and for a purpose, to be hereinafter disclosed. The drive for the mills or cutters 17', 17' has already been described in connection with the mills or cutters 17, 17 and the cradle operating mechanism has also been described in more or less detail. The mechanisms for reciprocating the slide 13 vertically and the slide 15 horizontally will now be described and the same 45 preferably consist of the following instrumentalities.

Fixed on the shaft 89 is a spur gear 132 that meshes with a similar gear 133 fixed on a horizontal shaft 134 journalled in suitable bearings in the column 6. The gears 132 and 133 preferably have equal diameters so that the shaft 134 will be driven at the same speed as the shaft 89. Fixed on the shaft 134 is a cam 135, the groove 136 of which is shaped so that during the first half revolution of the shafts 89 and 134 a portion of said groove is concentric with the axis of the shaft 134 and no motion is imparted to a rod 137, the lower end of which is provided with a roller engaging in the cam groove 136. During the second half revolution of the shafts 89 and 134, however, said rod is moved by a portion of the cam groove 136, to reciprocate the slides 13 and 15 vertically so that like motion is imparted to the rose end mills or

cutters 17', 17'. To this end, the rod 137 is pivotally connected at 138 with one extremity of a lever or walking beam 139 pivotally mounted at 140 on the overhanging head 7 of the machine. The opposite extremity of this walking beam is pivotally connected at 141 with one end of a two part rod 142 that is pivotally connected at 143 with the slide 13 and provided with a turnbuckle 144 whereby the length of the rod 142 may be adjusted as desired (Figs. 2 and 3). The rod 137 may also, if desired, be made a two part rod detachably connected together to provide for relative movement of its parts during raising and lowering of the slide 11 by means of the hand wheel 51, relative motion between the parts of the rod during the automatic operation of the device being prevented by suitable means, such as the clamping bolt 145' illustrated in Fig. 3. Any suitable form of guide for the lower end of rod 137 may be provided in order to prevent lateral motion thereof, the same not being illustrated in the drawings for the sake of simplicity and clarity.

Referring now to the slide 15 on which the spindles 16, 16 for the mills or cutters are journalled, this slide is reciprocated laterally or horizontally as it is being reciprocated vertically with the slide 13, and for this purpose the shaft 86 has fixed thereon a worm 145 that meshes with a worm wheel 146 secured on a horizontal shaft 147 journalled in suitable bearings in a housing portion 148 extending from one side of the column 6 (Figs. 1, 2 and 3). The shaft 147 extends through the housing portion 148, at the front of the machine and has fixed on the projecting end a cam 149, the groove 150 of which is so shaped that during the first half revolution of the shaft 89 and cam 90 a portion of the cam groove 150 is concentric with the axis of the shaft 147 and no motion is imparted to a rod 151, one end of which is provided with a roller 152 engaging in the groove 150. During the second half revolution of the shaft 89 and cam 90, however, the groove of the cam 149 acts to move the rod 151 and reciprocate the slide 15 horizontally. For this purpose the rod 151 is pivotally connected to said slide at 153, and has a toggle connection with shaft 147 through a link 151' suitably pivoted at its ends to said rod and shaft as clearly shown in Figs. 1 and 3 of the drawings.

Assuming now, that the machine has been set up for the profiling and undercutting of the work and that the mills or cutters 17', 17' are engaged with the work 32 in the shallower parts of the compression recesses 33, 33, the drive for the cutters is started to rotate the same, as by again throwing the switch for the motor 63, and the operator depresses the treadle 111 to establish the drive for the cradle and slide operating mechanisms

through engagement of the clutch elements 98, 99. After the drive for these various instrumentalities has been established, the shaft 89 and cam 90 make a second half revolution in the course of which the roller 126 rides onto the cam 127 which thereupon moves to the left (Fig. 3) as before and engagement of the roller 126 with the cam 127 disconnects the clutch parts 98, 99 and therefore stops the movement of the slide and cradle operating mechanisms at the end of the second half revolution of the shaft 89 and the cam 90. The positions of the relatively movable parts when the operation is stopped at the end of the second half revolution of the cam 90, is substantially the same as shown in full lines in Figs. 1 and 2 of the drawings.

During the second half revolution of the cam 90, however, the mills or cutters 17', 17', and the cradle and work 23, 32, are swung relatively and have relative rectilinear movements simultaneously imparted thereto in a plurality of directions that are angularly related to each other and to the direction of swinging movement. These relative movements result in a machining of the walls of the compression recesses 33, 33 in closed paths beginning and ending at the shallower parts of said recesses, and undercutting of said walls at the deeper portions of the recesses. These closed paths are identical in configuration and one of them is indicated diagrammatically in Fig. 6 where B represents the path of the axis of the cutter and C, D, E, F, G, H and I represent, in the order named, positions successively occupied by the cutter as the later and the work are moved relatively in the manner stated. The undercutting preferably begins at the position D, ends at the position H, and is greatest at the positions E and G where are located the deeper portions of the recess that lie over the valves when the head 32 is secured on the internal combustion engine.

In performing the machining and undercutting operation with the mills or cutters 17', 17', the latter and the work, as herein shown, are moved relatively in three planes each at right angles to the other two. The motion in a horizontal plane and in a direction toward and away from the deeper or valve pocket ends of the compression recesses, is obtained by swinging movement of the cradle 23 during the second half revolution of the cam 90. The cradle is swung as before by the cam 90 and the rod 94 and the shape of that portion of the groove of cam 90 which acts to swing the cradle during the second half revolution of said cam is such as to produce a greater swinging traverse of the cradle and work than is obtained during the initial cutting operation on the work by the cutters 17, 17. This greater swinging traverse of the cradle enables the mills or cut-

ters 17', 17' to machine and undercut at the extreme, deeper ends of the compression recesses.

The depth of the cut, during the machining and undercutting operation, is obtained by the vertical component of the motion of the swinging cradle and by the vertical motion of the slide 15 and cutters 17', 17', which during swinging movement of the cradle 23, are reciprocated vertically with the slide 13 by the cam 135, rod 137, walking beam 139 and rod 142. The width of the machining and undercutting is obtained by the horizontal motion of the slide 15 and cutters 17', 17' which, during swinging movement of the cradle 23 and vertical reciprocation of slide 13, are reciprocated horizontally or lengthwise of the cylinder head 32, by the cam 149 and rod 151.

In addition to the described simultaneous motions of the parts occurring in the course of the machining and undercutting operation, an additional motion is preferably introduced at this time lasting only for a predetermined interval of time in order to enable the mills or cutters 17', 17' to more readily machine and undercut adjacent the reentrant portions 32', 32' of the cylinder head. This additional motion is preferably imparted to the slide 19 near the end of the rearward traverse of the cradle 23 and varies the angular relation between the mills or cutters 17', 17' and the work during the time that the mills or cutters 17', 17' are adjacent the reentrant portions 32', 32' of the cylinder head in a manner clearly illustrated in Figs. 10 and 11 of the drawings. For the purpose of changing the angular relation of the mills or cutters 17', 17' with the work when said cutters reach the reentrant portions 32', 32' of the cylinder head, the shaft 134 has fixed thereon a pair of cams 153', 153', the grooves 154, 154 of which rotate concentrically with the shaft 134 during the major portion of a complete revolution thereof, so that no motion is imparted to a pair of rods 155, 155 provided with rollers 156, 156 engaged in the cam grooves 154, 154. These rods 155, 155 extend from the cams 153', 153' to opposite sides of the slide 19 and are pivotally connected therewith at 157, 157. It will be understood that suitable guide bearings, not shown, are provided for the ends of rods 155 adjacent the cam members 153. It will thus appear, that during the major portion of a complete revolution of the shafts 89 and 134, no motion will be imparted to the slide 19. During a predetermined interval in the machining and undercutting operation, to wit when the cradle 23 approaches the end of its rearward swinging traverse and the mills or cutters 17', 17' are adjacent the reentrant portions 32', 32' of the cylinder head, the cams 153', 153' and the rods 155, 155 impart a slight reciprocation to the slide 19 and this slight reciprocation of said slide 130

is converted into a slight forward and rear tilt of the cradle 23 that varies the angular relation between the work and the cutters 17', 17', enables the latter to more accurately follow the margins of the reentrant portions 32', 32', and undercut the walls of each reentrant portion 32', 32' to a depth that is somewhat less than the depth of the undercutting at the cutter positions E and G, shown in Fig.

10 6. The depth of the undercut at the position G is clearly shown in Fig. 10 and the depth of the undercut at one of the reentrant portions 32', 32' is clearly shown in Fig. 11.

In the machine herein illustrated, it is preferable to brace the yoke 20 by connecting one of its arms 22, 22 to the column 6, and as clearly shown in Fig. 2, this is accomplished by means that provide for reciprocation of the slide 19. Said means consists of a plunger 158 that is bolted at 159, 159 to a projecting part 160 of the yoke arm, and a bracket 161 bolted at 162, 162 to the column 6 and having a cylinder 163 in which the plunger 158 is slidably fitted.

25 25. As above pointed out, the roller 126 and cam 127 stop the operation of the machine at the end of the second half revolution of the cam 90, at which time the machining and undercutting has been completed so that the walls of the compression recesses 33, 33 are undercut substantially as indicated diagrammatically at K, K in Fig. 6 of the drawings. As herein disclosed, the cradle 23, during the initial cutting or machining operation, is

30 35. swung once toward the rear and then once toward the front of the machine, and said cradle, during the machining and undercutting operation receives a similar movement accompanied by reciprocation of the slides 13 and 15. It is to be expressly understood, however, that in either or both of these operations the cradle may be swung repeatedly and that during the machining and undercutting the slides 13 and 15 may be

40 45. repeatedly reciprocated through the employment of devices suitable for these purposes and embodying the principles of the above described cradle, clutch, and slide operating devices.

50 55. It is to be further understood, that while one embodiment of this invention is herein illustrated and described in detail, the invention is not limited thereto but may be embodied in a variety of mechanical expressions within the scope of the appended claims.

What is claimed is:

1. In a machine of the character described, a rotatable mill or cutter adapted to machine the wall of a cylinder head compression recess, a cradle mounted opposite the mill or cutter and arranged to swing on an axis extending transversely of the axis of rotation of the mill or cutter, said cradle being adapted to support a cylinder head thereon with the compression recess faced toward, and its

wall engaged with, the mill or cutter, means for rotating the mill or cutter, and means causing said mill or cutter to machine the entire wall of the compression recess and comprising mechanism for automatically swinging said cradle in opposite directions and mechanism for automatically reciprocating the rotating mill or cutter along a line substantially parallel with the axis of swing of the cradle and said cylinder head.

2. In a machine of the character described, a rotatable mill or cutter adapted to machine the wall of a cylinder head compression recess, a swinging cradle adapted to support the cylinder head with the compression recess faced toward, and its wall engaged with, the mill or cutter, a support on which the cradle is arranged to swing about an axis extending transversely of the axis of rotation of the mill or cutter, and means causing said mill or cutter to machine the entire wall of the compression recess and comprising mechanism for automatically swinging the cradle and cylinder head in opposite directions and mechanism for automatically reciprocating the rotating mill or cutter in the direction of depth of said recess and along a line substantially parallel with the axis of swing of the cradle and said cylinder head.

3. In a machine of the character described, a rotatable mill or cutter adapted to machine the wall of a cylinder head compression recess, a swinging cradle adapted to support the cylinder head with the compression recess faced toward, and its wall engaged with, the rotating mill or cutter, a slotted support on which the cradle is arranged to swing about an axis extending transversely of the axis of rotation of the mill or cutter, means causing said mill or cutter to machine the entire wall of the compression recess and comprising mechanism for automatically oscillating the cradle and the cylinder head and mechanism for automatically reciprocating the rotating mill or cutter rectilinearly in angularly related directions, and guide means for the oscillating cradle comprising a slotted rib or extension formed on the under side thereof and a guide block engaged in the slot of said rib and adjustably mounted in the slot of said support.

4. In a machine of the character described, a rotatable mill or cutter adapted to machine the wall of a cylinder head compression recess, a swinging cradle adapted to support the cylinder head with the compression recess faced toward, and its surface engaged with, the rotating mill or cutter, a support on which the cradle is arranged to swing about an axis extending transversely of the axis of rotation of the mill or cutter, said support having spaced parallel slots formed therein below the cradle, means causing said mill or cutter to machine the entire surface of the compression recess and comprising

mechanism for automatically oscillating the cradle and the cylinder head and mechanism for automatically reciprocating the rotating mill or cutter rectilinearly in a plurality of angularly related directions, and means for guiding the swinging cradle comprising spaced parallel ribs or extensions formed on the under side thereof and having curved slots therein, and guide blocks adjustably mounted in the slots of said support and having curved upper extremities engaged in the curved slots of said ribs or extensions.

5. In a machine of the character described, a pivotally mounted work support, a plurality of mills or cutters arranged to simultaneously engage work carried by the work support, means for rotating the mills or cutters, means for automatically shifting the axis of the pivoted work support toward and away from the mills or cutters during a portion of their cutting operation, and means automatically oscillating said work support while the tools are rotating and engaged with the work.

6. The combination with a machine tool, of 25 a pivotally mounted cradle having an opening in one side thereof, a device on an adjacent side of the cradle for clamping work to the opposite side thereof, an element pivoted on the cradle to swing across said opening, 30 and means for securing said element to the cradle before the work is clamped thereto, whereby the cradle is strengthened to withstand the force exerted by said clamping device.

35. 7. The combination with a machine tool, of means for supporting work to be machined by said tool, said means comprising a hollow swinging cradle open at its top and front sides and closed at the remaining sides, a device for clamping the work in the cradle under the open top side thereof, and a member 40 adapted to be secured to the cradle across the open front side thereof after the work has been placed in said cradle and before said 45 work is clamped therein by said device.

8. The combination with a mill or cutter, of means for supporting work to be machined by said mill or cutter, said means comprising a hollow pivoted cradle having an opening in 50 one side through which the mill or cutter is passed into and withdrawn from the cradle and an opening in another side through which the work is passed into and withdrawn from said cradle, means for clamping the 55 work in the cradle adjacent the opening therein for the mill or cutter, an element pivoted on the cradle to swing across the opening therein through which the work is passed, and means for detachably securing said element in position across said last-named 60 opening to strengthen the cradle against the force exerted by the clamping means.

9. The combination with a machine tool, of 65 means for supporting work to be machined by said tool, said means comprising a yoke or

the like, a cradle trunnioned on said yoke to swing the work during the machining operation, a rectilinearly movable screw shaft extending in said cradle, a hand-wheel for turning said screw shaft and retained in the cradle against displacement with the screw shaft, and a device mounted on said screw shaft within the cradle and adapted to clamp the work against a part of the cradle opposite said device.

10. The combination with a machine tool, of means for supporting work to be machined by said tool, said means comprising a yoke, a cradle pivoted on said yoke and provided in one side thereof with a slot, a rectilinearly movable clamp operating device extending in the cradle, a clamp rotatably mounted on said device, and a guide pin on said clamp engaging in said slot to prevent rotation of the clamp as the latter is moved by said operating device.

11. In an apparatus for machining recesses in cylinder heads for engines, a rotating tool, a work holder adapted to swing on an axis substantially perpendicular to the axis of the tool, and means for oscillating the work holder and traversing the tool substantially parallel to the axis of swing whereby the tool is caused to machine out a recess of varying width in the cylinder head.

12. In an apparatus for machining recesses in cylinder heads for engines, a rotating tool, a work holder, means for clamping a cylinder head in the work holder with the face to be machined adjacent the tool, and means for rocking the work holder and the cylinder head in opposite directions along a curvilinear path while the tool is in contact with said face, the axis about which said curvilinear movement takes place lying parallel to said face.

13. In an apparatus for machining recesses in cylinder heads for engines, a rotating tool, a work holder, means for clamping a cylinder head in the work holder with the face to be machined adjacent the tool, means for rocking the cylinder head in opposite directions along a curvilinear path while the tool is in contact with said face, the axis about which said curvilinear motion takes place being parallel to said face, and means for simultaneously moving the tool to and fro in a direction parallel to said axis.

14. In an apparatus for machining cylinder heads for multi-cylinder engines, a plurality of rotating tools, a work holder, means for clamping a cylinder head in the work holder in position for the tools to machine out a row of recesses in said cylinder head, and means for swinging the work holder in opposite directions along a curvilinear path during the machining operation, the axis about which said curvilinear movement takes place being parallel to said row of recesses.

15. In an apparatus for machining cylinder heads for multi-cylinder engines, a plurality of rotating tools, a work holder, means for clamping a cylinder head in the work holder in position for the tools to machine out a row of recesses therein, means for swinging the work holder in opposite directions along a curvilinear path, the axis about which said curvilinear movement takes place being parallel to said row of recesses, and means for simultaneously traversing the tools to and fro in a direction parallel to said axis during the machining operation. 5
16. In an apparatus for machining cylinder heads for multi-cylinder engines, a plurality of rotating tools, a work holder, means for clamping a cylinder head in the work holder in position for the tools to machine out a row of recesses therein, means for swinging the work holder in opposite directions along a curvilinear path, the axis about which said curvilinear movement takes place being parallel to said row of recesses, means for simultaneously traversing the tools to 10 and fro in a direction parallel to said axis, and means for advancing and retracting the tools with respect to the work to vary the depth of the recesses. 15
17. In an apparatus for machining compression recesses in cylinder heads for engines, the combination of a driven rose end mill, a pivoted work holder adapted to support a cylinder head with a compression recess thereof facing toward the mill, and means for automatically oscillating said elements relatively and simultaneously imparting relative rectilinear movements thereto in a plurality of directions that are angularly related to each other and to the direction of oscillating movement, whereby said mill is caused to machine the wall of the recess and undercut said wall at the deeper part of said recess. 20
18. In an apparatus for machining recesses in cylinder heads for engines, the combination of a rotary rose end milling tool, a pivoted work holder adapted to support a cylinder head with a compression recess thereof facing toward the mill, means for driving the tool, means simultaneously oscillating the work holder and reciprocating the tool rectilinearly across the path of travel of the work holder, and means for reciprocating the tool in the direction of the depth of the work, whereby said mill is caused to machine the wall of the recess and undercut said wall at the deeper part of said recess. 25
19. In a machine of the character described, the combination of a pivotally mounted cradle adapted to support a cylinder head having a compression recess therein, a driven, movably mounted rose end mill adapted to engage the wall of said recess and rotatable about an axis extending at right angles to the pivotal axis of the cradle, and means for 30 automatically moving the cradle and the mill relatively in different directions, whereby the latter machines the recess wall and undercuts it at the deeper part of the recess. 5
20. In a machine of the character described, the combination of a pivotally mounted cradle adapted to support a cylinder head, a driven bodily movable rose end mill adapted to machine a compression recess in said cylinder head and rotatable about an axis extending at right angles to the pivotal axis of the cradle, and means for oscillating and bodily moving the cradle and the mill relatively, whereby the mill machines a recess, the wall of which is undercut at the deeper part of said recess. 70
21. In a machine of the character described, the combination of a pivotally mounted cradle adapted to support a cylinder head, a driven bodily movable rose end mill adapted to machine a compression recess in said cylinder head and rotatable about an axis extending at right angle to the pivotal axis of the cradle, and means for moving the cradle and the mill relatively, whereby the latter machines a recess the wall of which is undercut at one part thereof, said means comprising devices for oscillating the cradle and devices for reciprocating the tool across the path of travel of the cradle and toward and away from the same. 75
22. In a machine of the character described, the combination of a cradle arranged to swing on a horizontal axis and adapted to support a cylinder head with the compression recesses thereof faced upwardly, a plurality of driven rose end mills arranged above the cradle to rotate on vertical axes and each adapted to engage the wall of one of the compression recesses, and means for automatically oscillating the cradle and the mills relatively and for imparting relative rectilinear movements thereto in a plurality of directions angularly related to each other and to the direction of oscillating movement, whereby the mills machine the walls of the compression recesses and undercut said walls at the deeper parts of said recesses. 80
23. In a machine of the character described, a pivotally mounted cradle, a vertically movable slide, a horizontally movable slide carried by the vertically movable slide, a rose-end mill or cutter mounted on the last-named slide and adapted to engage work supported on the cradle, and automatically operated means rotating the mill or cutter, reciprocating the slides, and swinging said cradle, whereby said mill is caused to machine and undercut said work. 105
24. In a machine of the character described, a vertically movable slide, a driven shaft journaled thereon, a horizontally movable slide carried by the vertically movable slide, a rose-end mill or cutter journaled on the horizontally movable slide and adapted 110
25. In a machine of the character described, a vertically movable slide, a driven shaft journaled thereon, a horizontally movable slide carried by the vertically movable slide, a rose-end mill or cutter journaled on the horizontally movable slide and adapted 120
26. In a machine of the character described, a vertically movable slide, a driven shaft journaled thereon, a horizontally movable slide carried by the vertically movable slide, a rose-end mill or cutter journaled on the horizontally movable slide and adapted 125

- to be rotated by said driven shaft, a pivotally mounted cradle adapted to support work that is engaged by the rotating mill or cutter, and automatically operated means reciprocating 5 said slides and oscillating said cradle so that the work thereon is machined and undercut by said mill or cutter.
25. In a machine of the character described, a pair of slides arranged to be reciprocated substantially at right angles to each other, a plurality of rose-end mills or cutters carried on one of said slides, means rotating the mills or cutters, a pivotally mounted cradle arranged to support work engaged 10 by the rotating mills or cutters, and means for automatically reciprocating the slides and swinging said cradle during rotation of the mills or cutters whereby said mills or cutters are caused to machine and undercut 15 said work.
26. In a machine of the character described, a mill or cutter, movable means on which the mill or cutter is mounted, a pivotally mounted cradle arranged to support work adjacent the mill or cutter, means for manually adjusting the movable supporting 20 means to engage the mill or cutter with said work, and means for thereafter automatically rotating the mill or cutter, oscillating 25 the cradle, and reciprocating said movable means in angularly related directions.
27. In a machine of the character described, a plurality of rose-end mills or cutters, movable means on which the mills or cutters are carried, a pivotally mounted cradle arranged to support work in engagement with the mills or cutters, and automatic 30 mechanism for simultaneously rotating the mills or cutters, swinging the cradle, and reciprocating said movable means in angularly related directions whereby the mills or cutters are caused to machine and undercut said work.
28. In a machine of the character described, a pair of slides movable in angularly related directions, a rose-end mill or cutter carried by one of the slides, a pivotally mounted cradle arranged to support work in engagement with the mill or cutter, means 45 for rotating the mill or cutter, mechanism for moving the slides in said directions, and devices for swinging the cradle during rotation of the mill or cutter and said movement of the slides whereby the mill or cutter is caused to machine and undercut said work.
29. In a machine of the character described, a slide, a second slide carried by the first slide and movable substantially at right angles thereto, a rose-end mill or cutter carried by one of the slides, a pivotally mounted cradle adapted to support work in engagement with the mill or cutter, means for rotating the mill or cutter, cam operated means 55 for reciprocating the slides, and means for swinging the cradle during rotation of the 60
- mill or cutter and reciprocation of the slides whereby the mill or cutter is caused to machine and undercut said work.
30. In a machine of the character described, a vertically movable slide, a shaft journaled thereon, means for driving the shaft providing for reciprocation of the slide, a horizontally movable slide carried by the vertically movable slide, a series of mills or cutters carried by the horizontally movable slide and adapted to be rotated by said shaft, a pivotally mounted cradle for supporting work that is machined and undercut by the mills or cutters, means for reciprocating 70 said slides, and means for swinging the cradle during rotation of the mills or cutters and reciprocation of the slides.
31. In a machine of the character described, a vertically movable slide, means for reciprocating said slide including a cam operated 75 lever or walking beam, a horizontally movable slide carried by the vertically movable slide, means for reciprocating the horizontally movable slide, a mill or cutter journaled on the horizontally movable slide, means for rotating the mill or cutter, a pivotally mounted cradle arranged to support work that is machined and undercut by the mill or cutter, and means for swinging said cradle during 80 rotation of the mill or cutter and reciprocation of said slides.
32. In a machine of the character described, a rose-end mill or cutter, movable means on which said mill or cutter is carried, means for rotating the mill or cutter, a pivotally mounted cradle arranged to support work in engagement with the mill or cutter, a pair of cam shafts, means operated by the cam of one shaft for reciprocating said movable means rectilineally in a plurality of angularly related directions, and means operated by the cam of the other shaft for oscillating 90 said cradle during the reciprocation of the movable means, whereby the mill or cutter is caused to machine and undercut said work.
33. In a machine of the character described, a slide, a second slide carried by the first slide, a mill or cutter journaled on one of said slides, means for driving the mill or cutter, a pivotally mounted cradle arranged to support work that is machined and undercut by the mill or cutter, a pair of cam shafts, means operated by the cam of one shaft for reciprocating the first slide, means operated 100 by the cam of the other shaft for swinging said cradle, and means for reciprocating the second slide across the path of travel of the first slide.
34. In a machine of the character described, a pair of slides, a rose-end mill or cutter carried by one of said slides, means for driving the mill or cutter, a pivotally mounted cradle arranged to support work in engagement with the mill or cutter, and mech- 105

anism causing the mill or cutter to machine and undercut the work and comprising cam operated means for swinging the cradle and reciprocating one of the slides and cam operated means for reciprocating the other slide.

35. In a machine of the character described, a pair of slides, a driving shaft journalled on one of said slides, a mill or cutter carried by the other slide and adapted to be rotated by the driving shaft, a pivotally mounted cradle arranged to support work that is machined and undercut by the mill or cutter, a pair of cam shafts geared together and adapted to be driven by said driving shaft, means operated by one cam shaft for swinging the cradle, means operated by the other cam shaft for reciprocating one of the slides, and means operatively connected with the driving shaft for reciprocating the other slide.

36. In a machine of the character described, a pivoted work support or holder, a slide mounted adjacent thereto, a second slide movable across the path of travel of the first slide, a plurality of rose-end mills or cutters carried by one of the slides and adapted to engage work on said work support or holder, means for driving the mills or cutters, and means automatically reciprocating the slides and oscillating the work holder whereby the driven mills or cutters are caused to machine and undercut the work.

37. In a machine of the character described, a slide, a main driving shaft journalled thereon, a second slide carried by the first-named slide and movable substantially at right angles to its path of travel, a mill or cutter carried by the second slide, worm gearing connecting the main driving shaft with said mill or cutter for driving the latter, means for reciprocating the first slide, and means for reciprocating the second slide.

38. In a machine of the character described, a pair of slides, a mill or cutter carried by one of the slides, means for driving the mill or cutter, means for reciprocating the slide on which the mill or cutter is carried, and means for reciprocating the other slide comprising a driven cam, a pivoted lever or walking beam operatively connected with the last-named slide, and a link connected at one end with the lever or walking beam and provided at its opposite end with a roller engaging said cam.

39. In a machine of the character described, a rose-end mill or cutter, means rotatably supporting said mill or cutter, means for driving the mill or cutter, devices reciprocating said supporting means in one direction and comprising a pivotally mounted lever or walking beam and a cam operated member for oscillating said lever or walking beam, means automatically reciprocating the mill or cutter transversely of the path of travel of its supporting means, a pivoted work supporting

cradle, and means oscillating the cradle during said reciprocating movements of the supporting means and the cutter, whereby the latter is caused to machine and undercut the work on said cradle.

40. In a machine of the character described, a pair of slides, one carried by the other and movable across its path of travel, a plurality of rose end mills or cutters mounted on one of the slides and adapted to engage work supported adjacent thereto, a driven shaft, and means automatically operated thereby while the mills or cutters are engaged with the work, for simultaneously rotating said mills or cutters and reciprocating said slides whereby the mills or cutters machine and undercut said work.

41. In a machine of the character described, a slide, a driven shaft carried thereby, a second slide mounted on the first slide for movement across its path of travel, a series of rose end mills or cutters mounted on the second slide, worm gearing connecting said driven shaft with said mills or cutters so as to rotate the latter during reciprocation of the slides, and means operated by said shaft for automatically reciprocating both of said slides during rotation of said mills or cutters whereby the latter machine and undercut work supported adjacent thereto.

42. In combination, a work holder, a tool, means automatically swinging said elements relatively in opposite directions and imparting relative rectilinear movements thereto in a plurality of angularly related directions, whereby the tool machines the work on said holder, and additional means adapted during the machining operation to automatically change the angular relation between the surface of the work and the tool for a predetermined time.

43. In combination, a work holder, a tool for machining work on said holder, means automatically swinging said elements relatively in opposite directions to machine certain parts of the work, means automatically imparting relative rectilinear movements to the work holder and tool in a plurality of angularly related directions to machine other parts of the work, and additional means for moving the work holder and the tool relatively to change their angular relation for a predetermined time and machine another part of the work.

44. In combination, a work holder, a mill or cutter for machining and undercutting work carried by said work holder, means for swinging the work holder and the mill or cutter relatively in opposite directions, to machine certain parts of the work, means automatically imparting relative rectilinear movements to the work holder and the mill or cutter during their relative swinging movement, to thereby machine other parts of the work, and additional means operating auto-

matically during one cycle of the machine to change the angular relation between the work and the mill or cutter for a predetermined time.

- 5 45. In combination, a movable support, a work holder pivotally mounted thereon, a tool adapted to machine work carried by the work holder, means for driving said tool, means oscillating the work holder, and means 70
10 adapted to reciprocate said support for a predetermined period during the oscillation of 75
said work holder.

46. In combination, a movable support, a work holder pivotally mounted thereon, a tool arranged to machine work carried by the work holder, means for driving the tool, means oscillating the work holder and the tool relatively and imparting relative rectilinear movements thereto in angularly related directions, and means adapted to move said support for a predetermined period during said relative movements of the work holder and the tool. 80

47. In combination, a movable support, a work holder pivotally mounted thereon, a plurality of tools arranged to simultaneously machine work carried by the work holder, means for driving the tools, means independent of said support for swinging the work holder and the tools relatively in opposite directions and for imparting relative rectilinear movements thereto in a plurality of directions angularly related to each other and to the direction of swinging movement, whereby said tools machine certain portions of the work, and means for moving said work holder support for a predetermined period of time during said relative movements to facilitate the machining of other portions of the work. 85

48. In combination, a slide or the like, a work holder pivotally mounted thereon, a tool arranged to machine work carried by the work holder, means for driving the tool, means for swinging the work holder and the tool relatively 90
45 in opposite direction and for imparting relative rectilinear movements thereto in a plurality of angularly related directions, whereby the tool machines certain parts of the work, and mechanism independent of said last named means for reciprocating the tool and said slide relatively at a predetermined time during the operation of the machine, whereby the tool machines another part of the work. 95

49. In combination, a slide or the like, a work holding cradle pivotally mounted thereon, a mill or cutter arranged to machine and undercut work carried by said cradle, means for rotating the mill or cutter, means for reciprocating the mill or cutter in angularly related directions, means for swinging the cradle, and means independent of the cutter and the cradle operating means and adapted to reciprocate said slide at a predetermined time 100
60 during the operation of the machine. 105

50. In combination, a support, a work holder pivoted thereon, a tool for machining work carried by said work holder, means for driving the tool, a driven shaft, connections between said shaft and the work holder adapted to oscillate the latter with respect to the tool, a second driven shaft, and connections between said last-named shaft and said support adapted while the work holder is oscillating to reciprocate the support for a predetermined period of time. 110

51. In combination, a slidable support, a work holder pivotally mounted thereon, a pair of slides connected together and each movable transversely of the other, a tool on one slide for machining work carried by said work holder, means for driving the tool including a driven shaft, a plurality of cam shafts, connections between said driven shaft and the cam shafts for driving the latter, means operated by certain of the cam shafts and reciprocating said slides to move the tool in angularly related directions, means operated by one of the cam shafts for swinging the work holder, and means operated by another of the cam shafts 90
20 for reciprocating said support for a predetermined time during reciprocation of the slides and swinging movement of the work holder. 115

52. The method of machining metal work, which consists in making a straight initial cut in the work, machining the work along one side of the initial cut, then machining said work from said side of the initial cut to the opposite side thereof, and thereafter 100
30 machining the work along the last named side of said initial cut. 120

53. The method of machining metal work, which consists in making a substantially straight initial cut in the work, machining the work along one side of the initial cut, then undercutting the work from said side of said initial cut to the opposite side thereof, and thereafter machining said work along the last named side of the initial cut. 125

54. The method of machining recesses in metal work, which consists in making an initial cut in the surface of the recess, and successively machining the recess surface along one side of the initial cut, undercutting a 110
40 portion only of the wall of the recess, and machining the recess surface along the opposite side of said initial cut. 130

55. The method of machining tapered recesses in metal work, which consists in making an initial cut in the surface of the recess, and successively machining the recess surface along one side of the initial cut, undercutting the wall of the tapered recess at the deeper part thereof, and machining said surface along the opposite side of said cut in a direction opposite that of the first named machining operation. 135

56. The method of machining tapered recesses in cylinder heads, which consists in 140

making an initial cut in the surface of the recess and successively machining the recess surface along one side of the initial cut from the shallower end of the recess toward 5 its deeper end, undercutting the wall of the recess at its deeper end from said side of the initial cut to the opposite side thereof, and machining said surface along the last named side of the initial cut from the deeper part 10 of the recess toward the shallower part thereof.

57. The method of machining metal work, which consists in simultaneously making a plurality of spaced initial cuts therein, and 15 machining the work in a plurality of curved paths produced by simultaneously cutting said work along corresponding sides of said initial cuts, then cutting the work from said sides of the initial cuts to the opposite sides 20 thereof, and thereafter cutting the work along the opposite sides of said initial cuts.

58. The method of machining tapered recesses in cylinder heads, which consists in making an initial cut in the recess wall, and 25 successively machining the recess wall along one side of the initial cut, undercutting the wall recess at the deeper part of the recess, and machining said wall along the opposite side of said initial cut.

59. The method of machining tapered compression recesses in cylinder heads, which consists in making an initial cut in the recess wall, machining the recess wall along one side of the initial cut and the recess from the 35 shallower part of the recess toward the deeper part thereof, and thereafter machining said wall along the opposite side of the recess and said initial cut.

60. The method of machining tapered compression recesses in cylinder heads, which 40 consists in making an initial cut in the recess wall from the shallower part of the recess toward the deeper part thereof, machining the recess wall along one side of the recess and the initial cut, then undercutting the recess wall at the deeper part of the recess and at 45 one end of the initial cut, and thereafter machining said wall along the opposite side of the recess and said initial cut.

61. The method of machining tapered compression recesses in cylinder heads, which 50 consists in simultaneously making a plurality of initial cuts in the several recesses, machining the recess walls in one direction along corresponding sides of the recesses and the initial cuts, then undercutting the recess walls from said sides of the recesses and the initial cuts toward the opposite sides thereof, and 55 thereafter machining the recess walls along the last named sides of the recesses and initial cuts in a direction opposite to that of the first named machining operations.

62. In an apparatus for machining recesses 60 in cylinder heads for engines, a rotatable tool, a work holder adapted to support a

cylinder head in position for the tool to machine out a compression recess in said cylinder head, and means for rocking the work holder and cylinder head together in opposite directions along a curvilinear path while the tool is in contact therewith, the axis about which said curvilinear movement takes place being substantially perpendicular to the axis of rotation of said tool.

63. In an apparatus for machining recesses in cylinder heads for engines, a rotatable tool, a work holder adapted to support a cylinder head in position for the tool to machine out a compression recess in said cylinder head, means for rocking the work holder and cylinder head together in opposite directions along a curvilinear path while the tool is in contact therewith, the axis about which said curvilinear motion takes place being substantially perpendicular to the axis of rotation of said tool, and means for simultaneously moving said tool to and fro in a direction parallel to said first named axis.

64. In an apparatus for machining cylinder heads for multi-cylinder engines, a plurality of rotatable tools, a work holder adapted to support a cylinder head in position for the tools to machine out a row of recesses in said cylinder head, and means for swinging the work holder in opposite directions along a curvilinear path during the machining operation, the axis about which said curvilinear movement takes place being substantially perpendicular to the axes of rotation of said tools.

65. In an apparatus for machining cylinder heads for multi-cylinder engines, a plurality of rotatable tools, a work holder adapted to support a cylinder head in position for the tools to machine out a row of recesses in said cylinder head, means for swinging the work holder in opposite directions along a curvilinear path during the machining operation, the axis about which said curvilinear movement takes place being substantially perpendicular to the axes of rotation of said tools, and means for simultaneously moving the tools to and fro in a direction parallel to said first named axis.

66. In an apparatus for machining cylinder heads for multi-cylinder engines, a plurality of rotatable tools, a work holder adapted to support a cylinder head in position for the tools to machine out a row of recesses in said cylinder head, means for swinging the work holder in opposite directions along a curvilinear path during the machining operation, the axis about which said curvilinear movement takes place being substantially perpendicular to the axes of rotation of said tools, means for simultaneously moving the tools to and fro in a direction parallel to said first named axis, and means for advancing and retracting the tools with respect to the work to vary the depth of the recesses.

67. In a machine tool, a work holder, a tool, means for advancing and retracting the tool with respect to said work, means for swinging the work while it is engaged with the tool, and means for traversing the tool parallel to the swinging axis of the work, all of said means being automatic in operation and the operation of each being coordinated with that of the others.
68. In an apparatus for machining recesses in cylinder heads for engines, a substantially vertical rotating tool, a work holder adapted to swing to and fro along a curved path beneath said tool, the plane of said swinging movement being substantially vertical, means for oscillating the work holder and means for simultaneously traversing the tool in a vertical plane substantially perpendicular to the plane of said swinging movement.
29. In testimony whereof I have signed this specification.

HENRY KREBS.
